WIDE RANGE AIR REGISTER

Robert C. Vroom, Montclair, N. J., assignor to
 Peabody Engineering Corporation, New York,
 N. Y., a corporation of New York

Application January 30, 1939, Serial No. 253,609.

16 Claims. (Cl. 158—1.5)

This invention relates to air registers or the like of the type having inlet air passages through which air is supplied to the register, and more particularly to an air register for use in a burner for liquid, gaseous or pulverized fuels.

The invention is applicable, for example, to air registers of the general type shown in the patent to Peabody, No. 1,527,214, dated Feb. 24, 1925, having a housing provided with a set of peripheral air doors which are adapted to be actuated so as to provide controllable air passages therebetween for supplying air to the register tangentially and causing the air to whirl or rotate therein as it advances to the burner throat. The fuel supply or atomizing means may be located at the axis or at the periphery of the burner throat.

In order to adapt this type of register to different fuel capacities the air doors may be adjusted to vary the opening therebetween or the doors may remain in fixed adjustment and the air pressure may be varied. Both of these methods have certain disadvantages. For example, when the air doors are adjusted, the direction and velocity of the air are altered as well as the quantity admitted to the register. This alters the rotary motion of the air within the register and changes the characteristics of the burner. On the other hand, if the doors remain in fixed position and the air pressure is varied, the velocity of the air passing through the register and the velocity of the air at the burner throat are altered, with a consequent tendency for decreased turbulence and decreased rapidity of mixture of air and fuel at low capacities.

It is an object of the present invention to provide an air register having means for adjusting the quantity of air supplied to the burner throat without altering the characteristics of the air flow within the register.

Another object is to provide an air control for an air register of the type above indicated which is capable of varying the quantity of air supplied to the burner throat without changing the total quantity or velocity of air passing through the register.

Another object is to provide an air register control which may be utilized to control the air supply to burners, fan inlet boxes or the like, without altering the internal structure or adjustment of the device.

Another object is to provide an air register control which automatically maintains a predetermined pressure drop through the register regardless of the operating capacity.

A further object is to provide an air register

having means for withdrawing and returning a controlled portion of the air prior to passage through the burner throat.

Another object is to provide a system of the above type in which the velocity of the air through the air doors, through the register structure and in the fuel zone, will be maintained substantially constant at all capacities, whereby the efficiency of mixture of the combustion air and fuel will remain constant at all loads.

Various other objects and advantages will be apparent as the nature of the invention is more fully disclosed.

Although the novel features which are believed to be characteristic of this invention are pointed out more particularly in the claims appended hereto, the invention will be better understood by referring to the following description, taken in connection with the accompanying drawings, in which a specific embodiment thereof has been set forth for purposes of illustration.

In the drawings:

Fig. 1 is a longitudinal sectional view through a register embodying the present invention;

Fig. 2 is a section taken along the line 2—2 of Fig. 1 showing the axial air return control plate;

Fig. 3 is a partial sectional view illustrating a different embodiment of the invention;

Fig. 4 is a detail view showing a different air control means;

Fig. 5 is a broken sectional view showing one means for maintaining a controlled pressure differential between the plenum chamber and the return chamber; and

Fig. 6 is a broken sectional view showing the invention applied to a furnace operating with natural draft.

Referring to the drawings more in detail, the invention is shown in Fig. 1 as applied to an air register structure forming a part of a burner which is disposed in the front wall 10 of a furnace. The wall 10 is formed of the usual refractory material and is provided with an opening 11 in which is positioned a ring of refractory blocks 12 having flared inner surfaces 13 forming the burner throat. A plate 14 may be secured over the front of the wall 10 by any suitable means and may comprise the support for the air register structure. An inner ring 15, forms the discharge opening of the air register. It may be attached to the plate 14 by suitable means, such as bolts 16.

The plate 14 supports a wind box or plenum chamber 20 comprising top plate 21, bottom plate 22, front plate 18 and rear plate 19, which are se-

55

cured by a suitable means, such as angle irons or the like, located at the various joints. The rear plate 19 is spaced from the plate 14 to form an air return chamber 21.

5 The air register is shown as comprising a front plate 25 attached to the front plate 18 by bolts 26 and having a hub 27 in which the fuel supply barrel 28 is positioned. A set screw 29 may be provided for holding the barrel 28 in any position of adjustment. The barrel 28 may carry a tip 30 and a diffuser 31, which may be positioned within the burner throat, and may be provided with a coupling member 33 carrying the fuel connections. The barrel 28 may be adapted to supply liquid, gaseous or pulverized fuel, and may comprise, for example, a liquid fuel atomizer of the wide range type such as described in Peabody Patent 1,628,424, dated May 10, 1927, in which the operating capacity or load is adjusted by controlling the fuel pressure.

10 The air register is shown as provided with a set of peripherally arranged air doors 38 which are mounted on spacers 39, carried on bolts 40 extending between the front plate 25 and a rear plate 41 and forming a support for the rear plate. The rear plate 41 may be provided with suitable sealing means, such as a ring 42 of soft material adapted to engage the rear plate 19 of the wind box so as to effect an air-tight joint. 15 The front plate 18 may have an opening 18a of a size to permit the entire air register to be removed therethrough when the supporting bolts 26 are removed. The front plate 18 may constitute the front baffle of the wind box and may be supported independently of the plate 14 if desired.

20 The air doors 38 may be provided with inwardly extending cams 44 having slots 45 engaged by pins 46 mounted in a ring 47. The ring 47 may be seated in a recess in the front plate 25 and may be actuated by a pinion 48 carried on a shaft 49 journalled in a boss 50 in the front plate 25 and actuated by an operating handle 51. Rotation of the shaft 49 by means of the operating handle 51 causes rotational movement of the ring 47, thereby shifting the cams 44 and varying the annular position of the air doors 38. It is to be understood, of course, that the air doors may be actuated by other control mechanism and that 25 they may be operated either in unison or independently as may be desired. Furthermore, the doors may be arranged in the form of a frustum of a cone, as shown in Patent 1,527,214, above mentioned.

30 The rear plate 41 terminates in an inner flange 55 which is spaced from the inner ring 15 to provide an annular air passage 56 therebetween. The flange 55, however, is preferably in substantial alignment with the inner ring 15 so that, in effect, a continuous air passage is provided from the register to the burner throat.

35 Suitable means may be provided for adjusting the opening of the air passage 56. In the embodiment shown, this means comprises a sliding ring 57 which is mounted within the flange 55 and is actuated by a rod 58 extending through the front plate 25 and provided with a handle 59. The ring 57 thus slides axially of the burner to variably adjust the opening of the air passage 56.

40 In certain instances it may be desirable to remove the return air from around the atomizer barrel near the axis of the air register or at the front of the register. This is accomplished in the present construction by a housing 65 positioned around the hub 27 and attached to the

45 front plate 25 by bolts 66. The housing 65 forms an annular air passage 64 around the hub 27, the front plate 25 being provided with a plurality of apertures 67 to permit passage of air from the air register into said passage. Adjusting means 5 comprising an adjusting plate 68 having a similar set of apertures 69 may be journaled about the hub 27 and may be rotatably adjusted by a handle 70 attached thereto and extending through a slot 71 in the front plate. A rotary 55 adjustment of the plate 68 accordingly varies the effective size of the apertures 67 through which the air passes from the air register into the passage 64.

60 The specific form of control means for controlling the air supplied to the passage 64 may, of course, be varied.

65 Combustion air may be supplied to the plenum chamber 20 by means of a fan 75 having a discharge duct 76 communicating with said chamber 20 and having an intake duct 77 communicating with the return chamber 21, an intake duct 78 communicating with the atmosphere and a duct 79 communicating with the housing 65. Dampers 80, 81 and 82 are positioned in the respective ducts to adjust the air flow therethrough. A damper 83 may be provided in the discharge duct 76 to control the air supply to the chamber 20. In certain instances either the chamber 21 or the passage 64, with their corresponding ducts, 70 may be omitted.

75 In the operation of the system thus far described, air is supplied under pressure by the fan 75 to the chamber 20 and passes between the air doors 38 into the interior of the air register 35 wherein it is caused to rotate, due to the angular position of said doors. It then passes to the burner throat wherein it is suitably mixed with the atomized fuel. A controlled proportion of the air is withdrawn through the return chamber 21 and returned to the fan by the duct 77. The pressure in the plenum chamber 20 may be controlled by the operation of the fan 75 and by the damper 83. The pressure in the return chamber 21 may be controlled by the damper 80 45 or by the position of the ring 57. Likewise, the quantity of air withdrawn axially of the register through the passage 64 may be controlled by the damper 82 or the plate 68.

80 At maximum load the dampers 80 and 82 may be fully closed so that no air is withdrawn through the return chamber 21 or the passage 64 and the full capacity of the air register is supplied to the burner throat. The velocity and direction of the air may be controlled by the setting of the air doors and by the pressure maintained in the plenum chamber 20. When the fuel supply is reduced by suitable adjustment of the atomizer or of the fuel pressure, as more fully set forth in Patent 1,628,424 above mentioned, 60 the air supply may be correspondingly reduced by adjusting the dampers 80 or 82, the ring 57 or the plate 68, so as to withdraw a portion of the air from either the return chamber 21 or the passage 64 or from both as may be desired. The 65 air supply to the burner throat is thus reduced without reducing the velocity in the air register, whereby the efficiency of air flow and the rapidity of mixing the air and fuel is maintained at various loads.

70 If, for example, the pressure in the return chamber 21 is greatly reduced, corresponding to a condition in which a large proportion of the air is returned and a small quantity is supplied to the burner throat, the pressure drop across the 75

air doors and through the air register increases and the velocity of the air within the air register and the total quantity of air pumped may be correspondingly increased. In order to avoid this, the pressure of the air supplied to the register may be varied to correspond to the changes in return pressure. This may be accomplished by manual adjustment of the damper 83 or it may be accomplished automatically.

One type of automatic control is shown in Fig. 1 as comprising a pressure line 90 communicating at 91 with the chamber 21 and having a branch 92 communicating with the duct 79, suitable valves 93 and 94 being provided to shut off one of these lines if the corresponding duct is not being utilized for air return purposes. The pressure line 90 is shown as connected to actuate a diaphragm valve 95, controlling fluid under pressure received by a line 96 from a source not shown and connected by a line 97, having a vent 100, to actuate a pressure motor, such as a bellows 98 which is connected by a linkage 99 to control the damper 83.

The valve 95 and the pressure motor 98 are so adjusted that the pressure in the plenum chamber 20, as controlled by the damper 83, is varied in the same sense as the pressure in the return chamber 21, or in the return duct 79, as the case may be, so as to maintain a predetermined pressure differential across the air doors or through the register, regardless of the quantity of air withdrawn and returned to the intake of the fan.

By returning the air from the return chamber 21 after it has been discharged from the register, the velocity of air through the doors and the rotational effect within the register are maintained constant. In case it is only required to maintain the velocity through the air doors constant, the air may be withdrawn axially through the duct 79. The relative quantities so taken may, of course, be controlled by the dampers 80 and 82 or by the control ring 51 and the adjusting plate 68. Ordinarily, air will be taken from only one of these locations, although, in certain instances, the two ducts 77 and 79 may be used at the same time. Obviously, either the chamber 21 or the passage 64 may be omitted if not required in any particular installation.

In a further embodiment of the invention shown in Fig. 3, the return air is taken from a point past the plane of fuel supply so that the quantity and velocity of air initially contacting the fuel remains unaltered as the operating capacity is varied. In this embodiment, the construction is generally similar to that of Fig. 1, with the exception of the back plate 41a. This plate 41a is provided with a curved conical inner surface extending past the plane of the diffuser 31. The blocks 12 are cut back, as at 102, and the inner ring 103 is curved inwardly to provide an air passage 104 corresponding to the air passage 56 of Fig. 1, but displaced toward the interior of the furnace.

The register thus forms a converging axial air discharge opening at the burner throat to increase the air velocity prior to impinging on the cone of fuel. The diffuser provides a central adjustable coaxial restriction for further controlling the zone of maximum velocity. The return passage communicates with the register peripherally at a point beyond the minimum flow area so that variations in return flow do not alter the condition of air flow through the register or at the point of impinging on the fuel. This con-

struction accordingly provides a uniform mixture of fuel and air and maintains uniform combustion conditions regardless of the load.

In Fig. 4 a different type of control is provided for the air passage 56. In this embodiment the ring 115 corresponding to the ring 15 of Fig. 1 is formed as part of the rear plate 41 and is provided with a flange 116 which bears against the plate 14. The ring 115 is provided with a plurality of apertures 117 through which the air 10 passes to the return chamber 21. For adjusting the effective size of these apertures, an inner adjusting ring 118 is provided having corresponding apertures 119 and journaled for rotary movement within the ring 115. This adjusting ring 118 may be provided with a rack 120 which may be actuated by a pinion 121 carried on a shaft 122 which extends through the front plate, not shown. Actuation of the shaft 122 causes the ring 118 to rotate so as to vary the overlap of 20 the apertures 119 and 117. The shaft 122 may be journaled in a plate 123 which may also secure the ring 118 against axial movement. Obviously, the construction may be varied, making the ring 118 axially adjustable, as shown, for example, in connection with the ring 51 of Fig. 1.

In Fig. 5 is shown an embodiment of the invention using a pressure relief valve to control the pressure in the plenum chamber 20 in accordance with variations in pressure in the return chamber 21 or vice versa. In this embodiment a pressure relief valve 125 is provided in a duct 126 interconnecting the discharge duct 16 and the return duct 77, the arrangement being otherwise similar to that shown in Fig. 1, with the exception of the bellows 98 and the actuating mechanism therefor, which may be omitted. The control, in this embodiment, may be effected by means of the damper 81 in the duct 82 leading to the atmosphere. Sufficient air may be supplied through the duct 82 to compensate for the air which is discharged into the furnace through the burner throat. A constant pressure differential is automatically maintained between the plenum chamber 20 and the return chamber 21 by means of relief valve 125. The quantity of air supplied to the burner throat may accordingly be regulated by suitable control of the damper 81.

The invention may also be applied to a furnace operating with natural or induced draft or at a subatmospheric pressure. Such an embodiment is illustrated in Fig. 6 in which a stack 130 is connected to the furnace through a flue 131. The return duct 77 may be connected to a duct 132 passing beneath the floor of the furnace and connected to the flue 131 or directly to the stack 130. The quantity of air passing through the duct 132 may be controlled by a damper 133. A damper 134 may be provided in the flue 131 for controlling the furnace draft. The arrangement is such that the return air from the return chamber 21 is passed directly to the stack. The duct 132 may be arranged so that the return air is utilized for cooling the furnace floor or the return air may be used for other purposes before being passed to the stack. Additional air for cooling the furnace floor may be supplied to the duct 132 through a duct 136 leading to the atmosphere and controlled by a damper 137. Such additional air supply may be used, for example, when the burner is operated at high capacity which involves the use of a minimum amount of return air.

It is to be understood, of course, that the air 75

control may be applied to air registers for various purposes, such, for example, as fan inlet boxes or the like. The term "air register," as used herein, is to be construed accordingly. Furthermore, 5 the invention is not limited to the particular construction of air register herein disclosed, but may be applied to various standard types of air registers for use with liquid, gaseous or pulverized fuel which may be supplied peripherally as well as axially, as shown, for example, in U. S. Patents No. 1,671,494, to C. R. Stewart, dated May 29, 1928; No. 1,790,395 to S. T. Warner, dated Jan. 27, 1931; and No. 1,865,983 to S. T. Warner, dated July 5, 1932. Furthermore, the gas may be supplied axially instead of through the peripheral chamber or various combinations of the liquid, gaseous and pulverized fuels may be employed.

Although a specific embodiment of the invention has been shown for purposes of illustration, it is to be understood that the invention is capable of various uses and that changes and modifications may be made therein as will be readily apparent to a person skilled in the art. Certain specific terms have been used herein 20 merely for convenience of description and not as a limitation on the scope of the invention. The invention is to be limited only in accordance with the following claims.

What is claimed is:

- 30 1. In combination, an air register having a discharge opening, air admission means including peripheral air admission ports to supply air to said register, and means to withdraw a portion of the air from said register after passage through said ports and prior to passage through said discharge opening, so as to control the quantity of air discharged therethrough.
- 40 2. In combination, an air register having a discharge opening, air admission means including peripheral air admission ports to supply air to said register, means comprising an air return passage communicating with said register at a point beyond said ports in the direction of air flow to withdraw a portion of the air therefrom after passage through said ports and prior to passage through said discharge opening, and means controlling the pressure in said air return passage to thereby vary the quantity of air withdrawn therethrough.
- 50 3. In combination, an air register having a discharge opening, air admission means to supply air to said register, means comprising air return passages communicating with said register at different zones to withdraw a portion of the air therefrom, and means controlling the pressure in each of said air return passages to thereby vary the quantity of air withdrawn therethrough, for thereby controlling the zone from which said return air is withdrawn from said register.
- 60 4. In combination, an air register having a discharge opening, air admission means including peripheral air admission ports to supply air to said register, means comprising an air return passage communicating with said register at a point beyond said ports in the direction of air flow to withdraw a portion of the air therefrom after passage through said ports and prior to passage through said discharge opening, and adjustable means controlling the flow of air in said return passage so as to vary the quantity of air withdrawn from said register.
- 70 5. In combination, an air register having a discharge opening, means supplying air to said register at a controlled pressure, means comprising an air return passage communicating with said

register to withdraw a portion of the air therefrom, means controlling the pressure in said return passage to thereby vary the quantity of air withdrawn therethrough and means varying the pressure of air supplied to said register in a sense 5 to maintain a predetermined pressure drop across said register.

6. In combination, an air register having a discharge opening, pressure means including a fan to supply air under pressure to said register, 10 means withdrawing a portion of the air from said register prior to passage through said discharge opening and means returning said portion to said fan for recirculation.

7. In combination, an air register having a set 15 of peripheral air doors adapted to admit a controlled quantity of air in a direction to form a rotating mass of air therein and provided with a discharge opening arranged to discharge the air axially of said register, means supplying air to 20 said register at a controlled pressure, and means to control the quantity of air discharged through said discharge opening, said control means comprising an air return passage arranged to withdraw a portion of the whirling mass of air from 25 said register, and means controlling the air pressure in said return passage for varying the quantity of air thus withdrawn.

8. In combination, an air register having a set 30 of peripheral air doors adapted to admit a controlled quantity of air in a direction to form a rotating mass of air therein and provided with a discharge opening arranged to discharge the air axially of said register, means supplying air to 35 said register at a controlled pressure, and means to control the quantity of air delivered through said discharge opening, said control means comprising an air return passage arranged to withdraw a portion of the whirling mass of air from within said register, means controlling the 40 air pressure in said return passage for varying the quantity of air thus withdrawn, and means varying the supply pressure in the same sense, so as to maintain a predetermined pressure drop across the air doors, whereby the air velocity 45 through said doors and the speed of rotation of the mass of air in said housing are unaffected by changes in operating capacity.

9. The invention set forth in claim 7 in which the return passage communicates with the interior of the register at a point near the axis of the rotating mass of air. 50

10. The invention set forth in claim 7 in which the return passage communicates with the interior of the register at a point remote from the axis of the rotating mass of air. 55

11. The invention set forth in claim 7 in which the return passage communicates with the periphery of the rotating mass of air so as to withdraw the portion centrifugally. 60

12. The invention set forth in claim 8 in which a control member is provided to vary the supply pressure and said member is actuated in response to changes in pressure in said return passage.

13. The invention set forth in claim 7 in which a differential pressure control system is provided to vary the supply pressure in accordance with changes in pressure in the return passage, so as to maintain a predetermined pressure drop across said register. 65

14. An air supply system for a burner having a throat and means to produce a cone of fuel therein for combustion, said system comprising an air register, means supplying air thereto at a controlled pressure, peripherally arranged air 70 75

doors in said register to admit a controlled quantity of said air thereto and to impart a whirling motion to said air, said register having an axial air discharge opening communicating with 5 said burner throat to supply air for combustion purposes, and means to control the air supply to said burner in accordance with changes in operating capacity while maintaining substantially constant air flow conditions within the 10 register, said control means comprising a return passage communicating with the register at said discharge opening to withdraw a portion of the air prior to passage through said throat, and means controlling the quantity of air withdrawn 15 through said return passage.

15. The invention set forth in claim 14 in which the return passage communicates with the burner throat beyond the point of the fuel supply whereby the rapidity of mixture of air and fuel is 20 not affected by changes in operating capacity.

16. An air supply system for a burner having a throat and means to produce a cone of fuel

therein for combustion, said system comprising an air register, means supplying air thereto at a controlled pressure, peripherally arranged air doors in said register to admit a controlled quantity of said air thereto and to impart a whirling motion to said air, said register having a converging axial air discharge opening to increase the air velocity prior to impinging on said cone of fuel, and a central adjustable coaxial restriction for further controlling the zone of maximum 10 velocity, said axial discharge opening communicating with said throat so as to supply air for combustion purposes and means to vary the air supply to said burner while maintaining substantially constant air flow conditions within said 15 register, comprising a return passage communicating with said register at the periphery thereof to withdraw a portion of the air from said axial discharge opening beyond the point of minimum flow area. 20

ROBERT C. VROOM.
